DESIGN FOR A MANICURE CASE

Wilson W. Brown, Kansas City, Mo., assignor to D. Stanley Seibel and Wilson W. Brown, doing business as The Willing Company, Kansas City,
Mo., a partnership

Application April 12, 1948, Serial No. 145,649

Term of patent 7 years

(Cl. D86—10)

To all whom it may concern:

Be it known that I, Wilson W. Brown, a citizen of the United States, residing at Kansas City, in the county of Jackson and State of Missouri, have invented a new, original, and ornamental Design for a Manicure Case, of which the following is a specification, reference being had to the accompanying drawing, forming a part thereof, in which Fig. 1 is a perspective elevational view of the manicure case embodying the invention, and Fig. 2 is a perspective view showing the manicure case in an open position.

I claim:

The ornamental design for a manicure case, substantially as shown.

WILSON W. BROWN.
